UNITED STATES PATENT OFFICE.

CHARLES C. CURTISS, OF GRAND RAPIDS, MICHIGAN.

DESIGN FOR SECTIONAL STORE FURNITURE.

46,248.

Specification for Design.

Patented Aug. 11, 1914.

Application filed April 27, 1914. Serial No. 834,871. Term of patent 14 years.

To all whom it may concern:

Be it known that I, CHARLES C. CURTISS, a citizen of the United States, and a resident of the city of Grand Rapids, in the county of Kent and State of Michigan, have invented a new, original, and ornamental Design for Sectional Store Furniture, of which the following is a specification, reference being had to the accompanying drawing, forming a part thereof, and which fully discloses the essential features and characteristics of the design, such that others may fully understand the same.

The figure is a perspective view of a section showing my new design.

My design comprises in its essential features a frame 1 fashioned at the top and bottom to receive a similar frame thereabove, and rest on a similar frame below according to the well known method used in building up sectional furniture. The frame 1 is closed at its front by a plurality of swingingly mounted doors 2, each having a glass front through which the article holding members 3 may be seen and any articles held by such members 3 will be clearly displayed. The doors are mounted one above

the other and side by side as shown to close the front of the section frame, suitable partitions being provided between the doors. The article holding members 3 each comprises a base member 4, end members 5, and intermediate partitions 6, which end members and partitions extend forward from the back of the said members 3 and downward at an incline as shown at 7 for substantially half the forward length of said end members and partitions, and thence forward horizontally to the front edge of said members, as shown.

The design of section as shown is of very striking and original appearance, and one pleasing and attractive to the observer.

I claim:

The ornamental design for sectional store furniture substantially as shown and described.

In testimony whereof, I have hereunto affixed my signature in the presence of two witnesses.

CHARLES C. CURTISS.

Witnesses:

GEO. H. DAKIN,
FRANK E. LIVERANCE, Jr.
